BATHTUB SUPPORT

Frank G. Brotz, Kohler, Wis.

Application April 29, 1932. Serial No. 608,246

3 Claims. (Cl. 4—173)

My invention relates to improvements in bath tub supports of the type whereby the bath tub is supported from the studding upon which the plastering or tiling of the wall is also supported, thereby preventing relative displacement of the tub and the plastered or tiled wall which ordinarily occurs, due to the settling and shrinkage of the joists, when the tub is supported upon the floor joists as is customary practice. This displacement causes an unsightly and unsanitary crack to appear between the wall and the tub, and permits water to seep behind the wall, causing damage.

It is an object of my invention to obviate this difficulty by supporting the bath tub from the same studding upon which the tiling or plastering is supported, thereby preventing relative movement of the two.

It is a further object of my invention to provide such a hanger which may be easily and quickly installed and adjusted, and which may be stamped or otherwise formed from sheet metal, thus allowing it to be cheaply manufactured.

I attain these objects by the mechanism illustrated in the accompanying drawing, in which Figure 1 is a perspective view of the bath tub support attached to a stud; Fig. 2, a side view of the support with the bath tub and a plastered and tiled wall in position; and Fig. 3, a front view of said support.

Similar numerals refer to similar parts throughout the several views.

The numeral 1 indicates the bath tub support or bracket which is the subject of my invention. This support is formed with rearwardly extending portions 2—2 adapted to overlie opposite sides of the stud 3, and is attached thereto by means of a single bolt 4. The support 1 has a forwardly extending portion 5 adapted to project for some distance beyond the stud 3.

The above described support is preferably formed from a single piece of sheet metal. It will, of course, be understood that, although I have shown the preferred form of my invention, other shapes than that shown may be adopted without departing from the spirit of my invention.

A slot 6 is cut in the upper part of the forwardly extending portion 5, and positioned therein, transversely of the support 1 and horizontally disposed, is a bar 7 tapped to receive an adjusting screw 8. A second slot 9 is formed in the lower portion of the extension 5 adjacent the stud 3, and a pressure bar 10 which may be of sheet metal is mounted therein transversely of

the support and vertically disposed. The pressure bar 10 may be held in place in this slot by any suitable means, as by bending over a portion of the ends.

The tub 11 has a downwardly extending flange 60 12 and a beaded rim 13 adapted to be plastered into the wall.

In the use of my invention a suitable number of supports, for example, three or four, depending upon the size and shape of the tub, are placed 65 in position on the studding as shown by Figs. 1 and 2, and secured by the bolt 4 which passes through a hole drilled in the stud 3. The tub is then placed in position so that the flange 12 is behind the adjusting screw 8 as shown in Fig. 2. 70

The tub is then raised or lowered and leveled by means of the adjusting screws 8. This provides a much more rapid and efficient means of leveling the tub than is possible where the tub is supported entirely on the floor joists, as is 75 the usual practice. Thus, by the use of my invention the total time necessary to completely install the tub is reduced materially. The bolt 4 acts as a pivot or fulcrum, allowing the greater portion of the weight of the tub to be borne 80 by the pressure bar 10, thus allowing the support to be constructed of sheet metal.

After the tub is positioned and leveled, the plastered wall 14 is formed on the lath 15 as usual, the wall extending downwardly far enough 85 to enclose the bead 13 of the tub. A tiled surface 16 may be used or not, as desired.

From the foregoing description it will be apparent that relative movement of the wall and the rim of the tub is impossible, since both are supported by the same studding. The support may be made of sheet metal, rendering it light 90 in weight and inexpensive of manufacture. It is readily installed and adjusted.

Modifications of the exact form shown will 95 suggest themselves to those skilled in the art, and I do not limit myself to the exact form shown but claim all constructions within the spirit of my invention and the scope of the appended claims.

I claim:

1. In a bath tub support, the combination of a bracket formed from a single piece of sheet metal and comprising rearwardly extending portions adapted to overlie a stud and a forwardly extending portion, means for attaching said bracket to a stud, slots in said forwardly extending portion, a bar positioned in said slots, an adjusting screw threaded in said bar, slots adjacent the juncture of said forwardly extend-

ing portion and said rearwardly extending portions and a second bar positioned in said slots and adapted to abut said stud.

2. In a bath tub support, the combination of 5 a bracket formed from a single piece of sheet metal and comprising a forwardly extending portion and a pair of rearwardly extending portions adapted to overlie a stud, means for attaching said bracket to a stud, slots in said forwardly 10 extending portion, a bar positioned in said slots, an adjusting screw threaded in said bar, slots adjacent the juncture of said forwardly extending portion and said rearwardly extending portions, and a second bar positioned in said second 15 mentioned slots, said second bar having bent over end portions adapted to retain said bar in said slots.

3. In a bath tub support, the combination of

a bracket formed from a single sheet of metal and comprising a substantially triangularly shaped forwardly extending portion and a pair of substantially rectangular shaped rearwardly extending portions adapted to overlie a stud, means for attaching said bracket to a stud, slots in said forwardly extending portion at a point substantially above the median point of said bracket, a bar positioned in said slots, an adjusting screw threaded in said bar, slots adjacent the juncture of said forwardly extending portion and said rearwardly extending portions at a point substantially below the median point of said bracket, and a second bar positioned in said second mentioned slots, said second bar having bent over end portions adapted to retain said bar in said slots.
